UNITED STATES PATENT OFFICE.

ROBERT JOHN, OF NEW YORK, N. Y.

FILM-DRYING APPARATUS.

Application filed July 14, 1923. Serial No. 651,500.

This invention relates to a film drying and rewinding machine, particularly one in which films which have been joined together in a film printing machine are dried and separated and eventually rewound.

The invention in its preferred embodiment is illustrated in the accompanying drawings, which form part of this specification and in which:

- 10 Figs. 1 and 1^a represent a plan view of the entire machine;
Figs. 2 and 2^a represent a side elevation thereof;
Fig. 3 represents an elevation of the right 15 end of the machine.

Fig. 4 represents a front elevation of the same end as in Fig. 3;

Fig. 5 represents a side elevation of the rear end of the machine;

- 20 Fig. 6 represents a plan view thereof;
Fig. 7 is a section of the center of the machine where the separation of films takes place;

Fig. 8 shows plan views thereof; and

- 25 Fig. 9 shows sections along the line 9—9 in Fig. 7 showing the films positioned within the drying chamber and also the position of the separating roller with respect to the films.

- 30 In the preferred embodiment of the invention, there is shown a framework denoted generally by the numeral 1 which supports two long drying chambers rectangular in section denoted by the numerals 2 and 3. 35 These drying chambers may be supplied with a drying medium such as air or heated gases by means of an electrically operated blower mechanism 4 in the rear of the apparatus and an electrically operated suction 40 device 5 at the front thereof communicating by vertical channels 6 and 7 with the horizontal drying chambers 2 and 3. At the front end of the apparatus there are provided rollers designated by the numeral 8 over which the incoming film is passed on its way through an inclined and enclosed passageway 9 leading to the horizontal passageway or chamber 2 and joining it at a point designated by the numeral 10. At this point

- 45 there is mounted a roller 11 which functions to permit a separation of the films, in the case where a master film and a printed film have been joined together or to separate a film from a supporting tape or belt. In the 50 case illustrated the belt and printed film

form a support for the master film. The master film 4 is returned to the front end of the apparatus along the inside of the chamber 2 and over a roller 12 to the rewinding reel 13. The printed film which is here 55 designated by the numeral 14 passes to the other end of the chamber 2 in contact with a supporting fabric which is provided in the form of an endless belt to support the film in its transit through the drying apparatus. 60 The fabric and film pass around a horizontally mounted pulley 15 and then enter the drying chamber 3, which they traverse to the end thereof, and passing over a roller 16 the film is rewound on a reel 17. The pulley 70 15 is driven by a pinion 18 in mesh with a worm 18' mounted on a shaft 19, which is rotated by a motor 20 in a suitable manner, and on this shaft 19 is provided a gear 21 meshing with a gear 22 on a shaft 23 which 75 extends the entire length of the machine and carries at its other end a bevel pinion 24 in mesh with a bevel gear 25 mounted on a shaft 26 supporting the reels and acting as a driving means therefor. The reels are 80 driven through a friction clutch mechanism comprising discs 27 and 28 held by springs 29 and 30. It will thus be seen that the reels 13 and 17 are driven at the same speed and by the same mechanism as is the pulley 85 15, so that the films will move uniformly through the apparatus.

The fabric belt 14' enters the apparatus through the passageway 9, passing under the roller 11 on its way around the pulley 90 15, and then goes through the drying chamber 3, over the small pulley 16; and then down around a pulley 31, over a small roller 32; and back into the passageway 9. The incoming films passing over the roller 8 meet 95 the belt at the roller 32. The master film is separated from the other film which may accompany it, and the fabric belt also, and passes over the roller 11 to the right, as viewed in Fig. 2^a, and is eventually wound 100 up on the reel 13.

An electric rheostat 32' is shown for the purpose of controlling the electric motor which operates the blower 5. A cover 33 may be provided in the central portion of the drying chamber 2 for the purpose of inspecting the junction point with the passageway 9, and also the roller 11.

This apparatus is particularly adapted for separating and drying two films which have 110

been stuck together, as, for example, in a printing process, and thereafter drying and rewinding them. For example, it may be used for separating and drying a master film and a printed film which have been subjected to the various operations of the printing process as described in my copending application Serial No. 651,501 for a film printing machine and method filed on even 10 date herewith.

As many apparently widely different embodiments of this invention may be made without departing from the spirit thereof, it is to be understood that I do not intend 15 to limit myself to any of the embodiments illustrated except as indicated in the following claims.

I claim:

1. A film drying apparatus comprising a long drying chamber and means to convey a film therethrough, an inclined passageway leading to the central part of said chamber, and means for conveying a plurality of films through the passageways to the chamber, 25 and means for separating the films at the said central part of the chamber.

2. A film drying apparatus comprising a long drying chamber and means to convey a film therethrough, an inclined passageway leading to the central part of said chamber and means for conveying a film therethrough to the chamber, and a roller at the said central part of the chamber to guide a film in said chamber.

3. A film drying apparatus comprising a long drying chamber and means to convey a film therethrough, an inclined passageway leading to the central part of said chamber and means for conveying a film therethrough to the chamber, and means for forcing a drying current of a gas through the chamber.

4. A film drying apparatus comprising two long drying chambers and a means to convey a film therethrough, an inclined passageway leading to the central part of one of the chambers and means for conveying a film through the passageway to the chamber, and a roller at the said central part of the chamber to guide a film in said chamber.

5. A film drying apparatus comprising two long drying chambers, an inclined passageway leading to the central portion of one chamber, a roller at the junction point, 55 means for conveying films into the passageway and therethrough into the chamber, means for conveying a film over the roller and out through the end of the chamber, and means for conveying a film out through the other end and through the other long chamber.

6. A film drying apparatus comprising two long drying chambers, an inclined passageway leading to the central portion of one chamber, a roller at the junction point,

means for conveying films into the passageway and therethrough into the chamber, means for conveying a film over the roller and out through the end of the chamber, means for conveying a film out through the other end and through the other long chamber, and an endless belt in the passageway and drying chambers for conveying films in a continuous circuit therethrough. 70

7. A film drying apparatus comprising a long drying chamber, means for conveying a film therethrough, a reel at the end of the chamber, and means for rotating the reel and conveying the film at the same rate of speed. 75

8. A film drying apparatus comprising a long drying chamber, means for conveying a film therethrough, a reel at the end of the chamber, and means for rotating the reel and conveying the film at the same rate of speed, 85 said reel being driven by a friction clutch mechanism to permit slippage if necessary.

9. A film drying apparatus comprising a long drying chamber, a passageway opening into said chamber, means for conveying a film and a support therefor through said passageway, means for separating the film from its support and means for conveying the film through the drying chamber. 90

10. A film drying apparatus comprising a long drying chamber, a passageway opening into said chamber, means for conveying a plurality of associated films through said passageway, means for separating the films, and means for conveying one of the films 100 through said drying chamber.

11. A film drying apparatus comprising a long drying chamber, a passageway opening into said chamber, means for conveying a film and a support therefor through said passageway, means for separating the film from its support, means for conveying the film through said drying chamber and means for forcing a current of drying gas through the chamber. 105

12. A film drying apparatus comprising a long drying chamber, a passageway opening into said chamber, means for conveying a plurality of associated films through said passageway, means for separating the films, means for conveying one of the films through said drying chamber, and means for forcing a current of drying gas through the chamber. 110

13. A film drying apparatus comprising a long drying chamber, a passageway opening into said chamber between the ends thereof, means for conveying a plurality of associated films through said passageway, means for separating the films, and means for conveying one of the films in one direction and another of the films in another direction through the chamber toward the ends thereof from the point at which the films are separated. 120

14. A film drying apparatus comprising a long drying chamber, a passageway opening into said chamber, means for conveying a film and a support therefor through said passageway, means at the junction of the passageway and chamber for separating the film from its support, and means for conveying the film through said drying chamber from the point at which the separation

10 takes place.

15. A film drying apparatus comprising a long drying chamber, a passageway opening into said chamber between the ends thereof, means for conveying a plurality of associated films through said passageway, means at the junction of the passageway and chamber for separating the films, and means for conveying one of the films through said

drying chamber from the point at which the films are separated.

16. A film drying apparatus comprising a long drying chamber, a passageway opening into said chamber between the ends thereof, means for conveying a plurality of associated films through said passageway, means at the junction of the passageway and chamber for separating the films, and means for conveying one of the films in one direction and another of the films in another direction through the chamber toward the ends thereof from the point at which the films are separated.

In testimony that I claim the foregoing, I have hereunto set my hand this 11th day of July, 1923.

ROBERT JOHN.
